(57) **CLAIM**

The ornamental design for tweezers for electronic circuit, as shown and described.

DESCRIPTION

FIG. 1 is a top isometric view of a tweezers for electronic circuit.

FIG. 2 is a left side elevation thereof, the right side elevation view being a mirror image thereof.

FIG. 3 is a top view thereof.

FIG. 4 is a bottom view thereof.

FIG. 5 is a front elevation view thereof; and,

FIG. 6 is a rear elevation view thereof.
